UNITED STATES PATENT OFFICE.

GEORGE MANIERRE, OF MILWAUKEE, WISCONSIN.

CAR LOADER.

Application filed November 14, 1921. Serial No. 514,972.

This invention relates to improvements in car loaders.

It is an object of the invention to provide a device of this character which may be introduced through the door of an ordinary box car and by means of which a conveyor may be driven so as to transport the goods to be loaded to any desired point within the car.

10 It is also an object of the present invention to provide in association with a conveyor of this nature a drive for the conveyor, and a device for adjusting the conveyor in a horizontal plane and in vertical planes.

15 It is also an object of the invention to construct the support for a conveyor of the character described to permit of the conveyor being shifted from a central point of support in opposite directions towards either end of the car and to maintain the adjustability of the conveyor in vertical and horizontal planes after it has been shifted or while it is being shifted.

20 25 The invention also contemplates the provision of means whereby the direction in which the conveyor transports the goods may be altered; this alteration may be effected independently of the adjustment of the conveyor carrying frame.

30 The invention also provides means for reversing the movement of conveyor supporting structure through the action of the prime mover without requiring any reversal of the prime mover itself.

35 The invention also contemplates the provision of means for supporting the loaded part of the conveyor and for preventing the sagging of the same, during its operation.

40 45 It also has the object of rendering the distance between the sprocket wheels of an endless conveyor chain adjustable within a rigid supporting structure, so as to retain the conveyor permanently in taut condition.

50 55 The invention furthermore has the object of providing means in connection with a conveyor of this character, for preventing the material which is being placed on the conveyor from one side of the same, to be thrown over the opposite side of the conveyor and to render these means adjustable, and whereby they may be adapted to properly function independently of the direction in which the goods are carried by the conveyor.

The invention also contemplates the pro-

vision of novel means for controlling certain elements of a supporting structure for a device of this kind, whereby these elements may readily be locked at any desired angular position relatively to each other, or may be released so as to assume different angular positions as required.

With these and numerous other objects in view an embodiment of the invention is described in the following specification and illustrated in the accompanying drawings, wherein:

Figure 1 is a top plan view of the assembled device introduced into a box car which is shown in horizontal section;

Figure 2 is a side elevation of the device in the box car, the latter being shown partly broken away;

Figure 3 is an end elevation of the assembled device, the box car being shown in vertical cross-section;

Figure 4 is a sectional view on a larger scale on line 4-4 of Figure 3;

Figure 5 is a sectional view on line 5-5 of Figure 4;

Figure 6 is a section on line 6-6 of Figure 5 to illustrate the conveyor chair and conveyor frame in side elevation;

Figure 7 is a longitudinal sectional view through the conveyor, frame and turntable;

Figure 8 is a top plan view of an end portion of the conveyor frame and of the conveyor, certain parts of the frame and conveyor being shown in horizontal section;

Figure 9 is a side elevation of an end part of the elevator frame, illustrating the adjusting device for a sprocket shaft on the conveyor;

Figure 10 is a section on line 10-10 of Figure 5 to illustrate a reversible worm drive;

Figure 11 is a sectional view on line 11-11 of Figure 5, showing a reversing gear and clutch;

Figure 12 is an elevation of a supporting arm and pivot posts, certain parts being shown in section;

Figure 13 is a sectional view taken on line 13-13 of Figure 12;

Figure 14 is a detail sectional view of parts illustrated in Figure 13, but in slightly different position;

Figure 15 is a sectional view on line 15-15 of Figure 13;

Figure 16 is a diagrammatical sectional view of a portion of a clutch band;

Figures 17 and 18 are perspective views of two similar clutch rings, and

Figure 19 is a sectional view of a sprocket adjustment mechanism.

5 The main support of the machine comprises a foundation 1, Figure 2, from which a standard 2 rises. Horizontal brackets 3 and 4 which are fixedly secured to the standard 2 serve for supporting a shaft 5 which is held against rotation therein by means of the centering screws 6 in the lower bracket, but which may be raised and lowered with respect to the standard 2 by means of a bevel gear mechanism 7,—of known construction 10 and therefore not shown in detail, which can be actuated through the ratchet device 8. This adjusting device for the pivot shaft 5 does not form the subject matter of the present application and is described in detail in other co-pending applications.

The pivot post 5 serves for rotatably supporting a relatively heavy arm 10 which is provided with brackets 11 and 12 embracing the post 5 and held against longitudinal displacement by a collar 13, Figure 12. The opposite end of this arm 10 is formed with horizontal plates 14 and 15 which, as shown in Figure 13, may be provided with a plurality of openings to receive a second pivot shaft 16 which is also held against rotation in these openings with respect to the arm structure 10. It is obvious that through vertical adjustment of the main pivot post 5 with respect to the standard 2 the secondary pivot shaft 16 also may be adjusted relatively to said post.

In pivotal connection with the secondary pivot post 16 an arm 17 is provided, this arm terminating in the brackets 18 and 19 40 which surround the post 16 and which are held against axial displacement thereon. This arm which is also constructed in the form of a box shaped casting similar to the arm 10, forms at its opposite free end a turntable support 20, as shown in Figures 5 and 7.

An upper flange 21 of the turntable support carries a ball bearing 22 on which the weight of a turntable 23 rests. Thrusts 50 exerted during the operation of the device in upward direction are also absorbed by the flange 21 through a ball bearing 25 which is inserted between this flange 21 and a ring 26 secured to the lower open end of the turntable 23.

An extension 27 is rigidly fastened to the turntable 23 and serves principally for supporting a framework consisting of a plurality of channel irons 28 on which a platform 29 supports the driving motor 30 of the device. This motor is shown in the present instance to be an electric motor on whose shaft a sprocket 31, Figure 4, imparts a driving movement through a chain belt 32 65 to a larger chain belt drive wheel 33 which is

freely rotatable supported by a shaft 34, Figure 5. The chain belt 32 and the sprockets 31, 33 about which this belt is trained, are enclosed in a suitable casing 36, as shown in Figures 1, 4 and 5.

The shaft 34 which is driven at a reduced speed from the motor 30 is at one end supported in a bearing 37, while its other end extends through and is supported by a bushing 38 in a bracket 39 which is fastened to the turntable 23.

The chain belt driven wheel 33, Figure 5, is keyed to a hub extension 40 of a sprocket 41 which is also loosely mounted on the shaft 34. The sprocket 41 is provided with clutch teeth 42 in opposition to the clutch teeth 43 of a collar 44 which is keyed on the shaft 34 and which is slidably thereon. A lever 45 which is pivoted on a bracket on the platform 29 is connected by a rod 46 with a shifting fork 47 engaging by means of pins in a well known way, and a groove is provided in the sliding collar 44 whereby upon displacement of the collar 44 to operative position, with respect to the clutch teeth 42 90 rotary movement may be transmitted to the shaft 34.

The sprocket 41 drives by means of a chain 48, Figures 4 and 5, a sprocket 49 which forms a part of a sleeve 50 rotatably mounted on a shaft 51, Figure 11, which is carried by brackets 52 and 53 rising from the extension 27 of the turntable. This sleeve 50 is united at one end with a bevel gear 54 for actuating a reversing clutch 100 mechanism. The reversing clutch mechanism includes primarily a transverse shaft 55 supported in bearing brackets 56 and 57 which also rise from the extension 27 of the turntable. The shaft 55 carries loosely 105 thereon the friction clutch members 58 and a ring 59 of friction material, as for instance fibre which is secured to the disc, so as to be rotated therewith. Bevel gears 60 are each keyed to one of the discs 58 and are in 110 permanent engagement with the bevel gear 54 so as to be driven in opposite directions simultaneously.

The drive of either of these bevel gears 60 is selectively transmitted to the shaft 55 115 through clutch devices adapted to be brought into frictional engagement with the fibre ring 59. As shown in Figure 11, the shaft 55 carries slidably near each of the bearings 56, 57 clutch rings 61 which are forcibly 120 rotated with the shaft by suitable splines and feathers. The ends of the rings 61 are equipped with brackets carrying links 62 pivotally secured therein and in pivotal connection at their free ends with arms 63, the 125 other ends of which are pivotally secured to brackets 64 on disc elements 65. The arms 63 which form a part of this toggle lever construction, are provided with hook shaped extensions 66. These hook shaped 130

extensions are in engagement with rings 67 secured at the front end of hub sleeves of discs 69 adapted to engage the friction rings 59 at the surface opposite to that on which 5 the discs 65 engage the same. Each disc 69 is keyed to an inner sleeve 70 which in its turn is keyed to the shaft 55. The disc 65, however, is slidably connected by a key with the disc 69 whereby upon rotation of the 10 discs 69 and 65 this rotation is transmitted through the sleeve 70 to the shaft 55.

In neutral position, Figure 11, there is no friction between the discs 65, 69 and the ring 59, or it is not sufficiently great to cause 15 the transmission of the rotary movement from the ring to the discs and the shaft 55. But if one toggle joint lever is actuated, the pertaining link 63 will press the disc 65 against one face of the friction ring 59, 20 and as the arm 63 swings at the same time about the pivotal attachment on the bracket 64, the noses 66 will exert a pressure outwardly against the ring 67 which is fixedly connected with the disc 69 thereby pulling 25 the pertaining disc 69 at the same time into frictional engagement with the fibre ring 57. The clutch discs 65 and 69 transmit their movement through the pertaining keys and sleeves to the shaft 55. This shaft, therefore 30 may be driven in one or the other direction, dependent upon the operative position of the right hand or left hand clutch ring 61.

Either of these clutch rings may be moved to operative position by means of a rod or 35 tubing 71, Figs. 4 and 11, which is slidably carried in angle pieces 72 on one of the beams. This slideable member is equipped near its ends with lugs 73 adapted to engage the ends of clutch shift levers 74 which 40 are pivotally secured at 75 to brackets on another beam 28. The shifting levers 74 are of well-known construction and provided with the bifurcated portions on which pins 76 enter the circumferential grooves of the 45 pertaining clutch rings 61.

In order to effect this shifting movement of the sliding member 71, a ring or collar 77 near the central portion of the same is provided with lateral pins which are grasped 50 by the front end of a link 79, the other end of which is in pivotal connection with the foot of a lever 80 pivoted in a bracket on the platform 29.

Upon a swinging movement of the lever 80 into one or the other direction, the slide rod 71 will also be moved longitudinally in one or the other direction and this movement will cause the clutch levers 74 to throw either of the two clutches to operative position.

The shaft 55 therefore will be rotated in one or the other direction and will communicate this rotation to a sprocket 90 which is mounted at one end of the shaft 65 and which is connected by a sprocket chain

91, Figures 3, 4, with a sprocket 92, Figure 10, fixed to a shaft 93 which extends through a casing 94. As may be seen from Figure 5, the support of the casing 94 is effected by lugs 95 and 96 on the two halves of the 70 casing, and bolted to brackets 38 and 97 on the turntable 23. The casing 94 forms bearings 99 and 100, Figure 10, for the shaft 93. Between these two bearings, the shaft 93 carries loosely, two worms 101 and 102 respectively, and the worm 101 is in driving engagement with a worm gear 103 on the shaft 34, Figs. 5 and 6. The worm gear 103, 75 is in fixed connection with a sleeve 104, Figure 5, loosely mounted on shaft 34, and having at one end a sprocket 105.

The other worm 102 which is also loose on the shaft 93 is in driving engagement with a larger worm gear 106 which is secured on a shaft 107 extending parallel to the 80 countershaft 34.

The operative selective connection of the worms 101 and 102 with the shaft 93 is effected by a clutch collar 108 which is slidably mounted on the shaft 93 and fixed 90 against rotation with respect thereto. This clutch collar 108 is provided on opposite faces with clutch teeth 109 adapted to engage upon displacement the clutch teeth 111, of the worms 101 and 102 respectively. 95 The clutch collar 108 which is driven with the shaft 93 is embraced by a shifting member 113 in pivotal connection at one end with a lever 114 which again is joined to a crank 116 by a second link 115. The crank 100 116 is secured to a rock shaft 117 and a lever 119, Figure 4, serves for imparting an oscillating movement to this rock shaft. Dependent upon the position of this lever, the shaft 93 may be caused to drive either 105 the worm gear 103 or the worm gear 106. As the direction of rotation of the worm gear shaft 93 itself again is made dependent upon the direction of rotation of the shaft 55, it is obvious that the worm gear 110 103 and the worm gear 106 may be driven 115 selectively in either direction.

The turntable or carriage 23 serves for supporting the conveyor mechanism through which the load dumped into the car may 115 be advanced to any desired position in the interior of the car. The conveyor mechanism comprises a frame structure 118, Figs. 4, 5, 6, 7, 8 and 9, composed of vertical side plates 120 which are reinforced near their 120 upper and lower edges by angles 121. Other angles 122 are directed inwardly from the side plates 120, Fig. 5, and rack bars 123 are associated with the lower set of longitudinal reinforcing angle irons 122. 125

In order to further reinforce the frame structure 118, transverse members 124 are disposed at intervals between the side plates 120 and connected thereto, and these transverse members 124 serve for the attachment 130

of longitudinal angle irons 125 extending over a relatively large part of the conveyor structure, and serving as supports for rollers of the conveyor chain. In alignment with these longitudinal roller guides 125, brackets 126 are mounted which have inclined surfaces 127 to assist in guiding the rollers of the conveyor upwardly and to facilitate thereby the proper movement of the conveyor about the sprocket wheels 128, 129 which are mounted in the interior of the conveyor structure near the ends.

The conveyor chain, as illustrated in Figs. 5, 7 and 8, comprises two parallel series, each of two sets of links 160, which series are interconnected by carrying plates 161. Some of these plates are equipped with upstanding flanges 162 to assist in advancing the material deposited on the conveyor during the movement of the same. The links 160 of the conveyor chain are pivotally interconnected by bolts on which the rollers 163 are freely rotatable. The rollers of the upper portion of the conveyor chain travel on the angle irons 125 and 127 so as to prevent the sagging of the loaded part of the conveyor chain.

Near the ends of the frame structure 120 shafts 166 for the sprockets 128 and 129 respectively, are mounted. These shafts are supported in bearing brackets 167 terminating in plates 168 through which the brackets are secured by screws 169 to the side wall of the frame structure. These screws pass through longitudinal slots 170, Figure 9, so as to render an adjustment of these bearing brackets feasible. The shafts 166 which pass through slots 165 in the plates 120, Figure 9, freely support the sprockets 128, 129 over which the two chains are trained. In order to counteract the tensioning strain which by these chains is exerted on the shafts and bearing brackets, the brackets are provided with extensions 171, Figure 8, which project towards the interior of the frame structure and which serve for receiving the adjusting pressure screws 172, the inner ends of which are freely rotatable in fixed angle brackets 174 on the walls 120 to which reference has been made above. As these extensions 171 are firmly connected with the brackets 126 for the chains, an adjustment of the brackets 167 will also result in an adjustment of the brackets 126. The latter are slidably supported on rods 173 which pass through slots 174 in brackets 175 connected with the transverse reinforcing elements 124. The sprockets 128 at one end of this structure may be rigidly secured to the pertaining shaft 166.

This shaft is positively driven by a sprocket 180 and a chain 181 of the ordinary construction which is also trained about a sprocket 182 on the other shaft 166. One of the strands of this endless drive chain 181

is partly looped about a sprocket 183, Figures 5 and 6, which is directly keyed to the shaft 34 near the left hand end of the same. Therefore, if the countershaft 34 is rotated upon suitable movement of the clutch lever 45, this movement is directly transmitted to the sprocket 183 and the sprocket chain 181, and this movement then is communicated directly to the conveyor chain including the links 160 as shown.

The sprocket 105 is connected through the sprocket chain 130 with another sprocket 131 at the end of a shaft 132 which is provided in a secondary tilting support or chair 133 of the frame structure, Figs. 5 and 6. This tilting chair or support 133 is mounted by means of one side wall in a pivot 134 carried on a bracket 135 which rises from the turntable carriage 23 and which is in alignment with the shaft 34. The other side wall of this carriage chair 133 is pivotally mounted on a bushing 138 which is placed about the shaft 34. It will be seen therefore that the chair 133 may be turned about an axis coincident with the axis of the shaft 34.

This chair is provided with rollers 140 covered with suitable friction material, which are in alignment with each other on each side of the chair and which project from the walls of the chair in direction towards the conveyor frame structure. Angle irons 141 projecting from the side plates 120 outwardly, engage the rollers 140 from above, while the lower reinforcing angle irons 121 engage the rollers from below, whereby the entire frame structure of the conveyor is guided in a rectilinear path fixed with respect to the tilting supporting structure 133.

In order to tilt the chair 133 about an axis which is in alignment with the axis of the shaft 34 and to effect thereby also a tilting of the entire conveyor frame about the same axis, the shaft 107, Figure 10, carrying the worm gear 106 is provided at that end which projects from the casing 94 with a pinion 142 which, as shown in Figures 5 and 6, is in mesh with a larger gear 143 mounted on a shaft which is supported on the chair. This gear 143 is mounted on one shaft 144 with two smaller gears 145, Fig. 6, the teeth of which engage gear sectors 146 rigidly secured to the chair 130. It is obvious therefore that if the worm gear 106 is forcibly rotated through suitable displacement of the clutch sleeve 108, on shaft 93, the chair 133 may be tilted from the straight position in which it is shown in Figure 8, to a slanting position, for instance, as shown dotted in Figure 2. It is also obvious that a return tilting movement can be effected by simply reversing the direction in which the shaft 93 is driven, and this reversal again is effected by the actuation of the clutch mechanism illustrated in Figure 11 and acting on the jack shaft 55 shown therein.

A longitudinal displacement of the conveyor frame structure on its supporting structure 133 is effected by the sprocket 131 on the shaft 132 which sprocket is driven through the chain 130 from the other worm gear 103. The shaft 132 carries the pinions 150 which are in engagement with the racks 123 fastened to the inner lower angle irons 122 of the frame structure. The shaft 132 being supported on the tilting chair 133 which latter is not displaceable in longitudinal direction, will therefore drive the rack bars 123 and displace the same and thereby also the frame structure forwardly or rearwardly depending upon direction of rotation of the sprocket 105. The engagement of the gears 150 with the racks 123 is permanently maintained independent of the tilting movement of the chair 130, as the frame structure is tilted with the chair. The movement of this frame structure forwardly or rearwardly is controlled by the reversing clutch illustrated in Figure 11, combined with the movement of the clutch 108 on the worm shaft 93.

From Figure 6 it will also be noted that the proper engagement of the chain 181 with the sprocket 183 (Fig. 5) is permanently maintained owing to the means thru which this strand of the sprocket chain 181 is forced to embrace or is partly looped about the lower part of the sprocket 183. These means are formed by idle sprockets, 185, coaxial with the bolts 185, Figure 6, which are secured in the tilting chair 133 and which may be adjusted with respect to the axis of the shaft 34 by being secured in brackets 186 adjacent the slots 187 in the chair. The brackets 186, owing to the engagement of the sprocket chain 181 have a tendency to slide towards the opposite or far ends of the slots 187. This tendency is counteracted by pressure screws 188 which impinge on the brackets 186 and which extend either thru the end flange of the chair structure 133, as shown at the left hand side of Figure 6, or through a threaded wall 189 provided in the chair for this purpose.

As an additional means for adjusting the tension of the drive chain 181 and conveyor 161, not only in the upper strand, the sprocket 180 is adjustably secured to shaft 166. This is effected by means of screws 306 passing through arcuate-slots 307 of the sprocket into the hub 305, Figs. 6, 8 and 19.

The mechanism by which the primary supporting arm 10 may be adjusted with respect to the stationary pivot post 5, is shown particularly in Figures 12 to 18. The non-rotatable shaft 5 carries between the brackets 11 and 12 of the arm 10 a drum 200 which is rigidly secured to the shaft. This drum 200 is surrounded by two clutch bands of the form illustrated in Figures 17 and 18. A similar drum 201 is

loosely secured on the post 16 which is rigidly mounted in the plates 14 and 15 of the arm 10. The arm 17, however, is freely rotatable by its brackets 18, 19 on the second post 16. Each of the drums, is embraced by a set of clutch rings or bands 202, 202' respectively, comprising two circular members in different horizontal planes, as indicated at 203 and 204, these circular members being connected by a vertical web 205 adjacent to which the ends of the members 203, 204 are provided with suitable fastening elements or lugs 206, 206', for the attachment of shackles.

Each clutch ring is shackled by one of the loops 206 to a wall of the supporting arm 10, and for this purpose eye bolts 210, 210' are secured to the spaced projecting lugs 206 and to the walls of the arm 10. A circumferential displacement of these clutch rings with respect to the arm 10 is thereby rendered impossible.

The two innermost lugs 206', however, of the two sets of clutch rings are interconnected by a toggle joint structure comprising the links 220 and 221 which terminate in forks 222 and 223 and which are in pivotal connection with the lugs 206' of these rings. The inner ends of the two links 220 and 221 are in pivotal and sliding association through a slot and pin connection with a central link 226. The central portion of the link 226 is pivotally attached to another link 230 which is movably connected with an arm 231 at the lower end of a rod 232 which is rotatably supported on the arm structure 10. If the handle 234 of the rod 232 is rotated to swing the arm 231, the toggle structure may either be extended or stretched as shown in Figure 13, or the toggle joint may be broken, as indicated in dotted lines in the same figure, or as indicated in Figure 14. When the arm 231 is swung into a position to break the toggle joint a tensile strain is exerted upon the lugs 206' to which the links 220, 221 are attached. This will cause the clutch rings to be tightened about their respective drums and will thereby secure the arms in that relative angular position to which they have been adjusted.

As the shaft 16 is rigidly associated with the arm 10 and as the drum 201 by the tightening of the clutch bands is held immovable with respect to the shaft 16, it is obvious that then the arm 17 cannot be rotated owing to the projection 240, Figs. 12, 13, which extends from the flange of the drum 201 into an opening of the second arm 17. In this way the two arms may be securely interlocked in any position to which they have been adjusted, as for instance, indicated in Figure 1 or in any other desired position.

For the purpose of adjusting the turn-

table 23 within the arm 17, a shaft 250, Fig. 12, is rotatably mounted in the arm structure 17 and is held against vertical displacement therein. In rigid connection with the lower end of the shaft 250, the latter carries a small sprocket gear 251 over which the sprocket chain 252 is trained, this sprocket chain also being placed about a gear ring 253, Fig. 5, which forms a part 10 of the lower flange 26 of the turntable. As this lower flange is connected by bolts with the turntable 23, the latter together with the extension 27 secured thereto, may be rotated about the axis of the turntable 15 whenever this is desired. From Figure 5 it will be noted that idler sprockets 255 are rotatably mounted on the arm 17 in order to maintain the sprocket chain 252 in operative engagement with the gear 253 of the turntable.

On that side of the box car opposite to which the standard 2 is located, a chute 270, Fig. 3, may be disposed by means of a suitable upright structure 271 which is rotatably carried on a foundation 272. This chute may be extended forwardly in direction towards the box car by a movable section 273 the position of which may be adjusted through suitable lowering or raising 30 of a pivotal arm 275 which forms a part of the upright structure 271. The chute section 273 is yieldingly supported on this arm 275 by a rod 276 having a spring 277 which at one end presses against a collar 278 on the 35 rod and at the other end acts on a fixed plate 279. An additional support for these chutes near the inner end, may comprise a bracket 280 which is rigidly mounted on the top of the side wall of the tiltable carriage 40 123, whereby even upon a movement of the entire conveyor frame structure in a horizontal plane or in a vertical plane, the inner end of the chute section 273 may be adapted to deliver material to the endless conveyor.

Means are also provided for preventing the material which is thrown on the conveyor from the chutes from being projected across the conveyor and dropping on to those parts of the mechanism which serve 45 for driving the conveyor and for adjusting the same. A bracket 290, Figs. 5 and 3, which is mounted on the tiltable carriage 123, supports by means of bearings a shaft 292, Fig. 5, which is held against longitudinal displacement thereon. The inner end of this shaft supports rigidly the hub of a plate or disc 294 acting as a guard, and to this disc another curved plate 295 is riveted, which is bent so as to form a part of a hood 50 extending transversely of the conveyor. The shaft which projects through the bracket 290 carries rigidly thereon a crank or handle 296, Fig. 6, whereby upon the rotation of this shaft and by means of the crank the protector plate 295 may be swung from one

position to another position so as to prevent the material thrown onto the conveyor from falling too far backward in a direction opposite to that in which the conveyor intends to carry it. Other brackets 298 on the chair 133 serve for supporting a stationary guard plate 299 in opposition to the chute, Fig. 6.

The operation of the device will probably be understood from the above. When the entire device is not in use, the arm 17 may be pivoted about the shaft 16 of the arm 10 so that it forms an acute angle with this arm, and the turntable 23 and extension 27 may be rotated to place the extension in a position approximately parallel to the arm 17, whereby the entire device is arranged in a compact form, so as to obstruct as little as possible the path of the rolling stock. When a box car to be loaded has been moved into proper position so as to be adapted to receive the material from the chute 270, the two doors on opposite side walls of the car are opened and the loader is introduced into the box car through suitable actuation of the hand wheel 257 on top of the shaft 250, whereby the conveyor frame structure is angularly adjusted with respect to the secondary arm 17 and the latter may then be suitably adjusted by hand with respect to the primary supporting arm 10. The two arms 17 and 10 are angularly adjustable by hand, and may be locked in each adjustable position through breaking of the toggle joint connection through which the clutches on the upright posts of these pivotal structures are firmly connected with their posts. After the conveyor has been moved into the interior, as for instance, indicated in Figure 1, the material may be introduced through the chute on the conveyor and the latter may be operated by means of the motor and the clutches described, to carry the material first to a point near the left hand end of the box car, as shown. Through angular adjustment of the turntable with respect to the supporting structure 17, or through angular adjustment of the supporting structure 17 to the arm 10, or through a combination of these adjustments the conveyor may be moved parallel to itself from a point near one side wall of the car to a point near another side wall of the car, while at the same time the chute is extended through an adjustment of the arm 275 so that the material is always moved by gravity directly over the conveyor. After the car has been filled to a certain level, the worm gear clutch may be actuated to tilt the carriage 123 whereby the entire frame structure is also tilted upwardly to convey the material to a higher point of the car, and while the structure is tilted in a vertical plane it may also be moved transversely of the car either through the adjustment of the arm structures 10 and 17 or it may

be swung about the axis of the turntable by operation of the hand wheel 257. In this way one side, as for instance, the left hand side, Figure 1, of the car may be 5 filled entirely with bulk material, whereupon the worm gear clutch 89 may be thrown to the left, Fig. 10, to shift the conveyor frame structure by means of the transmission 101, 105, 130, 131, 123, without interruption of its operation, so as to 10 extend towards the right hand end of the car where this operation is also carried out, until finally both of the ends of the car are filled almost from bottom to roof with the 15 bulk material. The conveyor frame structure may then be completely withdrawn through the opening through which it has been introduced and this door may then be closed. The chute will then continue to discharge 20 material towards the central portion of the box car without requiring a conveyor for uniformly distributing the material in the interior of the car.

I claim:

1. In a car loader of the type having a conveyor traveling in a frame which is longitudinally displaceable with respect to a chair tiltably supported on a turntable, including a motor fixed to the turntable, a 25 counter shaft driven by the motor, a second counter shaft driven from said first named counter shaft, worms normally loose on said second counter shaft, worm gears on opposite sides of said second counter shaft and 30 permanently in engagement with said worms, said worm gears being operatively connected with means for longitudinally displacing the frame in the chair, and with means for tilting the chair with respect to the turntable respectively, and manually 35 controllable means for operatively connecting either of said worms with said second counter shaft.

2. In a car loader of the type having a conveyor traveling in a frame which is longitudinally displaceable in a chair tiltably supported on a turntable, including a motor secured on a turntable, a counter shaft driven fixed to the turntable, a counter shaft driven by the motor, means on the counter shaft 45 for driving the conveyor, a second counter shaft parallel to said first named counter shaft and adapted to be driven thereby, selectively reversible gearing driven from said second counter shaft, a worm shaft, a driving connection between said reversible gearing and said worm shaft, worm gear transmissions controlled by said worm shaft, and mechanisms under control of said worm transmissions for longitudinally displacing 50 the frame and for tilting the chair respectively.

3. In a car loader of the type having a conveyor traveling in a frame longitudinally displaceable in a chair which is tiltably

supported on a turntable, including a motor 65 fixed to the turntable and movable with the same, a counter shaft supported on the turntable and having its axis permanently parallel to the axis of the motor, another counter shaft parallel to said first named 70 counter shaft and driven by the same, reversible gearing driven from said second counter shaft, a worm shaft at right angle to said first named counter shaft and driven from said reversible gearing, a set of worm 75 gear transmissions selectively operable from said worm shaft, means controlled by said worm transmission for effecting longitudinal displacement of the conveyor frame with respect to the chair, and tilting movement 80 of the chair with respect to the turntable respectively, means for controlling rotation of said first named counter shaft, means for controlling selectively the reversible gearing, and means for selectively connecting the 85 worm transmissions with the worm shaft, all of said control means being accessible from a point above the turntable and adjacent the motor.

4. In a car loader of the type having a conveyor traveling in a frame which is longitudinally displaceable with respect to a chair tiltably supported on a turntable, including a motor fixed to the turntable and movable with the same, a counter shaft 90 driven by said motor, a second counter shaft driven from said first named counter shaft and parallel thereto, reversible gearing controlled by said second counter shaft, a worm 95 shaft operable in either direction from said reversible gearing, worms loosely mounted on said worm shaft, worm gear transmissions operable by said worms, one of said worm gears being loosely supported on said first named counter shaft and being operatively connected with the conveyor frame. 100

5. In a car loader of the type having a conveyor traveling in a frame which is longitudinally displaceable in a chair tiltably supported on a turntable, including an extension to the turntable, a motor fixed on said extension, a counter shaft driven by said motor, another counter shaft driven by said first named counter shaft, reversible 110 gearing supported by said extension and driven by said second counter shaft, a worm shaft driven by said reversible gearing, worm gear transmissions adapted to be brought selectively into operative connection with said worm shaft, and means controlled 115 by said worm gear transmissions for successively effecting longitudinal displacement of the frame with respect to the chair and for tilting the chair with respect to the turntable 120 respectively.

6. In a device of the character described, the combination of an endless conveyor, a frame structure for the same, rollers form-

- ing parts of said conveyor, longitudinal guides for the rollers, carried by the frame structure, sprocket wheels supported in the frame structure and over which the conveyor chain is trained, and means for guiding the rollers in proximity to the sprocket wheels, said last named guides being angularly disposed with respect to the longitudinal guides.
- 10 7. In a device of the character described, the combination of an endless conveyor chain, a frame structure for the same, rollers forming parts of the endless conveyor chain, sprockets supported by the frame structure, and over which the conveyor chain is trained, brackets adjustably mounted in the frame structure and supporting the sprocket wheels, and guides associated with said brackets to be adjustable with the same for supporting the rollers in their movement in proximity to the sprocket wheels.
8. In a device of the character described, the combination of an endless conveyor, a motor for actuating the same, a frame structure for the conveyor, a tilting support on which the frame structure is carried, the frame structure being provided with guide-ways and the tilting support having rollers co-acting with said guide-ways, means controlled by the motor for longitudinally displacing the frame structure on said guide-ways and rollers, and means controlled by the motor for tilting said support.
9. In a device of the character described, the combination of an endless conveyor, a motor for actuating the same, a countershaft from which the drive of the conveyor is derived, a supporting structure for the conveyor, and means for tilting said support about the axis of said countershaft.
10. In a device of the character described, the combination of an endless conveyor chain, a motor for actuating the same, a countershaft driven by said motor and from which the drive of the conveyor is derived, a supporting structure partly suspended from said countershaft, and motor controlled means for tilting said supporting structure and conveyor about an axis in alinement with the axis of the countershaft.
11. In a device of the character described, the combination of an endless conveyor chain, a motor for actuating the same, a countershaft driven by said motor, a sprocket fixed to said countershaft, and a sprocket chain trained over said sprocket and adapted to drive the conveyor, a frame structure for the conveyor, a tiltable support for the frame structure, the means for supporting said frame structure being in axial alinement with said countershaft, means partly mounted on said countershaft for longitudinally displacing the frame structure with respect to its support, and means under control of the motor for swinging
- said support about the axis of the countershaft.
12. In a device of the character described, the combination of a conveyor chain, a frame structure for the same, a motor for driving the conveyor chain, means controlled by the motor for longitudinally displacing the frame structure, a driving chain disposed on the outside of the frame structure and under the control of the motor, a sprocket wheel for the drive chain in a relatively fixed location with respect to the motor, and means for maintaining engagement between said last named sprocket and the drive chain independent of the position of the frame structure with respect to the motor.
13. In a device of the character described, the combination of a conveyor chain, a motor for actuating the same, a frame structure for the chain, a chair supporting the frame structure, a turntable on which the chair is movably carried, and means for selectively moving said frame structure or chair with respect to said turntable, the motor being fixedly related to said turntable.
14. In a device of the character described, the combination of a conveyor chain, a motor for actuating the same, a frame structure for the chain, a chair for supporting the frame structure, a turntable carrying the chair, an arm structure and means for selectively moving the frame structure, chair or turntable with respect to said arm structure.
15. In a device of the character described, the combination of a conveyor chain, a supporting structure for the conveyor chain, a turntable on which the supporting structure is mounted, an arm united with said turntable, another arm from which said first named arm is movably supported, and means on said first named arm for imparting a rotary movement to the turntable.
16. In a device of the character described, the combination of a conveyor chain, a supporting structure for the same, a motor for actuating the conveyor chain, a platform for the motor, a turntable on which the platform is mounted, an arm carrying the turntable, means in said arm for displacing the turntable relatively to said arm, and another arm to which said first named arm is movably connected.
17. In a device of the character described, the combination of a conveyor chain, a motor for actuating the same, a supporting structure for the conveyor chain, a turntable on which the motor and supporting structure is mounted, an arm supporting the turntable, another arm in pivotal relation to said first named arm, and means for locking the two arms in any desired angular position.
18. In a device of the character described,

the combination of a turntable, a conveyor chain, a supporting structure carried by the turntable and supporting the conveyor chain, an arm on which the turntable is rotatably mounted, a pivotal support for said arm, another arm, a pivotal support for said other arm, the two arms being united on said first named pivotal support, and means for maintaining the two arms locked in any angular position.

19. In a device of the character described, the combination of a conveyor chain, a supporting structure for the same, an arm carrying said supporting structure, another arm, pivotal posts from which said arms are supported, discs mounted on said posts, clutch bands surrounding said discs, and means for tightening or releasing said clutch bands with respect to their discs, whereby said arms may be locked or released respectively with respect to their supporting posts.

20. In a device of the character described, the combination of a conveyor chain, a supporting structure for the same, an arm carrying said supporting structure, another arm in pivotal connection with said first named arm, a post on which said second arm is pivotally supported, and a toggle joint structure for fixedly connecting said arms to their pivotal supports.

21. In a device of the character described, the combination of a conveyor structure, an arm rotatably supporting the same, a pivot post on which said arm is loosely mounted, another arm carrying said pivot post, another pivot post for said second arm, clutch rings associated with said posts, clutch bands, surrounding said rings and normally loosely thereon, and means for tightening said clutch bands to prevent relative move-

ment of said posts and of the arms carried thereby.

22. In a device of the character described, the combination of a conveyor structure, an arm rotatably supporting said conveyor structure, a pivotal support for said arm, another arm in pivotal connection with said first named arm, a pivotal post for said other arm, and means for simultaneously locking or simultaneously releasing both of said arms with respect to their pivotal supports.

23. In a device of the character described, the combination of a conveyor structure, an arm carrying the same, a pivotal support for said arm, another arm, a pivotal support for said other arm, rings secured on said pivotal supports, clutch bands surrounding said rings, and means on said second arm for tightening and releasing simultaneously said clutch bands, with respect to said rings.

24. In a device of the character described, an endless conveyor, a drive chain for the same, and means independent of each other for adjusting the tension in the upper and lower strand of the drive chain.

25. In a device of the character described, the combination of an endless conveyor, a drive chain for the same, a sprocket about the lower portion of which a drive chain is looped, adjustable means for decreasing and increasing the length of the chain in an engagement with the driving sprocket, said adjusting means acting on that strand of the chain which is looped on said sprocket, another sprocket for the drive chain, and means for adjusting the other sprocket to influence the other strand of the chain.

In testimony whereof, I affix my signature at 85 Oneida St., Milwaukee, Wisconsin.

GEORGE MANIERRE.
